UNITED STATES PATENT OFFICE.

EARL S. GIBSON, OF RIDGEWOOD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed August 10, 1923. Serial No. 656,742.

To all whom it may concern:

Be it known that I, EARL S. GIBSON, a citizen of the United States of America, residing at Ridgewood, in the county of Bergen and State of New Jersey, have invented certain new and useful Improvements in Telephone-Exchange Systems, of which the following is a full, clear, concise, and exact description.

This invention relates to telephone exchange systems and more especially to systems wherein machine switching apparatus under the control of operators is employed for establishing connections.

15 The object of the invention is an improved system in which provision is made for completing connections to certain lines regardless of their busy or idle condition.

20 A feature of the invention relates to a system arranged for extending connections over the lines of a group, such as private branch exchange lines, with provision for extending a subsequent call to one of said lines although the line may actually be busy 25 at the time.

Another feature relates to a system of 30 this character in which an operator by means at her disposal may affect the switching apparatus such that it disregards the busy condition of a trunk of a private branch exchange group and seizes one of the trunks thereof to extend a subsequent call.

Other features and advantages contemplated by this invention will be taken up in detail hereinafter and also pointed out in the appended claims.

Considering the drawing Figs. 1 to 14, inclusive, taken in the order illustrated in 40 Fig. 15 disclose enough of the details of a telephone system to give an understanding of the features of the present invention.

Fig. 1 shows a trunk circuit incoming to the central office from a distant office.

45 Fig. 2 illustrates an incoming selector switch of the coordinate type in which terminate trunks incoming from the distant office.

50 Fig. 3 shows a second group selector switch to which connections are extended from the incoming switch in Fig. 2.

Fig. 4 illustrates a final or connector

switch also of the coordinate type used for completing connections to called subscribers' lines and to private branch exchanges. 55

Fig. 5 shows a second final selector switch similar to the one illustrated in Fig. 4.

Fig. 6 discloses an operator's keyboard, an impulse sending mechanism located in the same office with the switches shown in Figs. 60 2, 3, 4 and 5.

Fig. 7 shows a coordinate sender selector switch for extending the incoming trunks into connection with one of a number of register sender mechanisms. 65

Figs. 8, 9 and 10 illustrate details of one of the register senders.

Fig. 11 shows a sender connector device for associating the senders with the incoming marker. 70

Fig. 12 shows the incoming marker which controls a plurality of incoming selectors to which it is common and with which it is associative.

In the lower part of Fig. 13 is illustrated 75 a multi-contact relay sender connector device for connecting the senders with the line marker. In the remainder of Fig. 13 and in Fig. 14 there is shown the line marker which is associative with the group 80 selectors and connector switches of Figs. 3, 4 and 5.

The disclosure illustrates a terminating 85 central office employing coordinate machine switches for completing connections to called subscribers' lines. This office is arranged to cooperate with distant manual offices.

Calls originating in the distant manual offices are routed over trunks which lead to the terminating office and are under the control and supervision of cordless operators in the latter office. These incoming trunks from the originating offices terminate in any suitable manner in the incoming automatic switches. It is the duty of the cordless operators 90 to make the necessary assignments orally to the distant operators by means of an order wire and to bring about release of the equipment at the proper times. The cordless operators on receiving the designations orally, set them up on the keyboard,

95 with the result that these records are transferred by code impulses from the operator's position to the register senders, which in 100

turn, control the switches to complete the connections to the called lines.

It may happen that a call is received in the terminating office from a long distance office or toll point which desires connection to a private branch exchange trunk group in the terminating office. Owing to the relative importance of such calls the cordless operator who attends to the assignment of 5 the trunk may be pressing a special key, set up a no test condition. Because of this no test condition, the switches in the terminating office will seize upon a trunk in the private branch exchange group even though 10 the same is busy at the time and thereby force the connection, whereas under other circumstances the switches would refuse to make the connection.

20 *General description of the system and apparatus.*

The selective switches including the incoming selectors 200, group selectors 300, connectors 400 and 500 and sender selector 25 switches 700 employed in this system are of the coordinate type such as shown and described in British Patent 183,436 to Western Electric Company, Limited, allowed August 23, 1923, and further shown and described 30 in U. S. Patent 1,517,331 to S. B. Williams, issued December 2, 1924.

The trunk 100 incoming from the distant manual office appears in the vertical row of contacts 201 of the incoming selector switch 35 200 and has access to all horizontal links 205, 206, etc. This incoming selector is shown in schematic form, only a limited number of the vertical rows of contacts and a limited number of the horizontal links being 40 illustrated. A second incoming trunk 212 is shown appearing in the vertical row of contacts 202. In the same manner other trunks incoming from the same or distant offices would appear in this and other equivalent incoming selector switches.

The incoming switch 200 also has a plurality of groups of outgoing trunks appearing in rows 203, 204, etc. Each outgoing trunk is shown having an appearance before 50 a single horizontal link. These trunks are multiplied in order to appear before corresponding horizontal links in all of the remaining incoming selector switches controlled by the same marker mechanism. The 55 trunks outgoing from the incoming selector switch are distributed among the different group selectors 300, one of these trunks 211 being shown in full.

A convenient manner of arranging the 60 group selector and connector switches is to make a division of the exchange into terminal line groups. For a 10,000 line office each terminal line group, for example, would have access to 2,000 different lines and 65 would comprise a number of group selector

and connector switches 300 and 400 and a single controlling line marker common to all of these switches. Each of the remaining four terminal line groups would likewise comprise a proper number of group selector 70 and connector switches and a line marker for controlling said switches. According to this plan the trunks outgoing from the incoming switches 200 would be distributed among the group selectors 300 in each of the 75 remaining line groups in order that any one of the 10,000 lines might be accessible.

Considering the terminal line group, the group selectors 300 are equipped with a number of groups of outgoing trunks which 80 lead to the various groups of connector switches including switches 400 and 500. Two of these trunks 322 and 325 are illustrated.

There will be as many connector switches 85 as are necessary to accommodate the 2,000 subscribers' lines, together with provision for as many P. B. X. trunks as may be required. Each of the several direct subscribers' lines is provided with a directory number and occupies a given position in one of the connector switches. Moreover, for each group of P. B. X. trunks there is a single call-line which has a directory number identifying the P. B. X. and which is located in 90 the connector switches along with the regular subscribers' lines. The several trunks belonging to each private branch exchange group represented by a call number line are, however, independent of the directory numbers. In other words, for each P. B. X. call-line there may be as many trunks outgoing to the distant P. B. X. as desired and these trunks may be located in one or a number of connector switches in an arbitrary 100 manner. In order to call a group of P. B. X. trunks the operator sets up on her keyboard a number identifying that particular P. B. X. group. The apparatus in the exchange establishes a connection through the 105 incoming switch to a group selector of the proper terminal line group and thence from the group selector to the particular connector switch in which appears the corresponding call-line. Immediately that the call-line is selected, connection through the group selector and connector switches is released and is automatically reestablished through the group selector and the proper connector to the first idle P. B. X. trunk of the required group. If this first trunk is located in the same connector switch with the call-line then the connection is reestablished to the connector switch first used. However, the first idle trunk may appear in a different connector switch, in which case, the re-established connection leads to such other connector switch and thence to the selected 115 idle P. B. X. trunk.

Considering the terminal line switching 120 125 130

Considering the terminal line switching 130

apparatus shown in the drawing there are illustrated a number of direct subscribers' lines 434, 435, 530 appearing in the connector switches 400 and 500. There is also illustrated a P. B. X. call-line 438 appearing in the switch 400 and a number of P. B. X. trunks 436, 437, 439, 523 and 524 comprising the group represented by the call-line 438. It will be understood, as previously explained that all of these P. B. X. trunks may be located on a single P. B. X. switch or they may be distributed among several connector switches. All numbered lines including both direct subscribers' lines and P. B. X. call-lines appear in the connector switches in groups of vertical rows according to their numbers. For instance, the vertical row of contacts 432 in the switch 400 represents a group of ten lines. Only three of these lines are illustrated in the drawing, the two subscribers' lines 434 and 435 and the P. B. X. call-line 438. In the second switch 500 (shown) the vertical row 520 represents another group of ten numbered lines. In like manner there will be as many of these vertical ten line groups in these and other connector switches as is necessary to accommodate the full 10,000 numbered lines. In addition to the numbered lines, P. B. X. groups also appear in vertical rows either exclusively or together with numbered lines as desired. The particular group shown occupies all of the vertical row 433 in the switch 400 and also a vertical row 521 in the connector switch 500.

The connector switches are also provided with a number of groups of horizontal links, each group having access to all numbered lines of a particular units designation together with P. B. X. trunks. For example, the group of links containing the links 401 and 402 have access to the call-line 438 in the row 432, to the trunk 436 in the row 433 and also to other lines or trunks in other rows (not shown). The horizontal test link 403 is associated with this group of horizontal links and serves for test purposes as hereinafter described. For each of the remaining nine units designations, there is a group of these horizontal links having access to lines and trunks. In a similar manner the switch 500 has a number of groups of horizontal links of which the links 501, 502 and 503 are a portion.

The incoming marker shown in Fig. 12 includes a series of test relays 1200 which serve to test the horizontal links in any of the incoming selector switches and also to test the outgoing trunks to which these links have access. The connecting device 1202 which comprises a number of multi-contact relays 1204, 1205, 1206, etc. serves to connect the set of test relays 1200 with the proper group of outgoing trunks, the multi-contact relays each being individual to a

different group. Another connecting device 1201 consisting of multi-contact relays 1208, 1209, 1210, etc. serves to connect the marker testing relays with the individual incoming switches. Relays 1208, 1209, 1210, 70 for instance, are individual to the particular switch 200 shown in the drawing. Relays 1220, 1221 and 1222 similarly are individual to another incoming selector switch. The line marker shown in Figs. 13 and 14 includes a plurality of registers 1400, 1401 and 1402 which receive numerical records from the senders. It also includes the multi-contact relay translating device 1404 which is operated according to the settings 75 of these registers to select the magnets 415, 416, 508 and 509 individual to the different vertical rows of lines in the connector switches. Moreover, the line marker includes a multi-contact relay device 1403 80 which operates to associate the register 1401 with connecting devices 410 and 516 individual to the proper connector switch 400 or 500. The device 410, for example, consists of relays 411, 412, etc. and serves to associate certain test relays in the marker with the horizontal links of the group having access to the called lines of the desired units designation in the connector switch 400. In Fig. 13 a set of testing relays in 90 the marker is shown, and these relays are associable through the multi-contact relay device 301, 302, with the groups of trunks outgoing from the selector switch 300 and other switches and also with the horizontal 95 links of these selectors.

The operator's position illustrated in Figs. 1 and 6 is equipped with a number of sets of keys 600, 601, 602 and 603 for recording the four digits of the called subscriber's number or of the private branch exchange group. Moreover, the position is equipped with certain impulse generating mechanism whereby code impulses are originated in accordance with the record on the keyboard 105 and transmitted to the associated sender. The operator's keyboard is further provided with an assignment key 118 and a release key 119 individual to each of the incoming trunks, the keys mentioned being individual 110 to the trunk 100. Also a no-test key 640 is provided by means of which the operator may set up the no-test condition to cause the seizure of a busy private branch exchange trunk. 115

Establishment of a connection to a group of private branch exchange trunks.

Consider that a connection is to be established between trunk 100 incoming from a 125 distant operator's position through the switches 200, 300 and 400 to an idle trunk in the private branch exchange group. In the first instance it will be assumed that the particular incoming call is not one of the 130

preferred calls and that no reason exists for bringing about a no-test operation. Furthermore, it will be assumed that the number of the P. B. X. call-line 438 which 5 serves the desired groups of trunks is 1 3 2 6.

Assignment of an idle trunk.

When the operator in the distant office receives the call she communicates over an 10 order wire not shown to the cordless operator in the terminating office and requests the assignment of an idle trunk and at the same time gives the cordless operator the number of the P. B. X. call-line. Complying 15 with this request the cordless operator assigns the trunk 100 for use and at the same time depresses the assignment key 118. The depression of the assignment key 118 causes the contacts of the associated release 20 key 119 to close, the contacts being normally open. When key 118 is depressed a circuit is completed from battery through the winding of relay 108, left contacts of key 118 to ground. Relay 108 closes a circuit 25 from ground through its inner right contact, winding of relay 105 to battery. Relay 108 locks in a circuit through its inner left contact, conductor 122, inner left back contact of relay 116, conductor 124 to 30 ground through the left contacts of key 119. Relay 105 completes a circuit from ground through its right contact, lamp 120 to battery. The lamp 120 is illuminated steadily.

Relay 108 also closes a circuit from battery through the winding of relay 109, outer left contact of relay 108, conductor 136, outer left contact of relay 610, right back contact of relay 609, right back contact of relay 608, to ground. Relay 109 operates in 40 this circuit and associates the operator's keyboard and equipment shown in Fig. 6 with the trunk 100, the keyboard being common to a number of these trunks. Relay 198 locks through its inner upper contact, conductor 123, winding of relay 609 to ground at the outer right back contact of relay 608. Relay 609 operates and relay 109 locks in this circuit. The operation of key 118 and the closing of the contacts of key 119 result in the closure of a circuit for 50 operating the sender selector switch 700 to associate the trunk 100 with an idle register sender. This circuit may be traced from ground through the left contacts of key 119, conductor 124, conductor 125, inner right back contact of relay 112, conductor 126, lower back contacts of relay 110, conductor 127, winding of relay 713 to battery. Relay 713 is individual to the trunk 100 and 60 serves to initiate the operation of the sender selector switch to associate an idle register sender with said trunk.

Relay 713, in operating, closes a circuit from battery, through the winding of relay 65 715, right back contact of relay 714, inner

right contact of relay 713, conductor 734, winding of relay 735 to ground.

Relays 714, 715 and 716 enclosed within the broken rectangle pertain to the vertical group of contacts in the row 701 of the 76 switch 700. These relays are brought into action whenever one of the trunks appearing in this row is seeking to be attached to a register sender.

Relay 715 completes a circuit from battery through the winding of relay 719, left contact of relay 715, conductor 734, winding of relay 735, to ground. Relay 715 also closes a circuit from battery through the left-hand winding of relay 716, right front contact of relay 715, left back contact of relay 717, outer right contact of relay 723 to ground through the winding of relay 735. Relay 716 at its outer left contact closes a circuit for relay 714. Relay 714 locks in a circuit through its winding and left contact and the contacts of relays 719 and 720 to ground. Relay 716 also closes a circuit from battery through its right winding and right contact, winding of relay 717, outer right back contact of relay 723 to ground through the winding of relay 735. Relay 717 operates and closes a circuit from battery through the winding of slow-to-release relay 722, outer right contact of relay 717, inner right back contact of relay 723 to ground through the winding of relay 735. Relay 722 operates and closes a substitute holding circuit for relays 716 and 717 independent of relay 723. With relay 717 operated a circuit is closed from battery through the winding of the vertical magnet 729, outer right front contact of relay 716, left front contact of relay 717, and thence to ground as above traced. Magnet 729 operates and prepares the contacts of the vertical row 701. Magnet 729 also closes a circuit from ground through its contact, conductor 736, left contact of relay 721, inner left contact of relay 716, outer right contact of relay 713, left-hand winding of relay 712 to battery. Relay 712 is a group relay individual to the group of horizontal links including the links 707 and 708.

Relay 712 operates and closes a circuit from battery through its right winding and right font contact, winding of relay 721 to ground over conductor 736. Relay 721 operates in this circuit.

Another circuit is closed from battery through the winding of the vertical magnet 731, brush 727 of the allotter 726, contact of slow-to-release relay 725, left contact of relay 723, inner right front contact of relay 717 to ground through the winding of relay 735. It is assumed that the first sender to which the circuit 732 leads, is idle and that the allotter switch 726 is standing in a position to allot this particular sender as shown.

The allotter 726 has a position for each of the several senders appearing in the sender selector switch 700.

As above noted the vertical operating magnet 731 relative to the idle sender operates and prepares the contacts in the vertical row 704. Magnet 731, in operating, completes a circuit from battery through its winding and inner contact, winding of relay 723, inner right contact relay 717, winding of relay 735 to ground. Relay 723, however, being shunted by the circuit above traced does not operate at this time. Magnet 731, furthermore, closes a circuit from ground through its outer contact, conductor 740, brush 728 of the allotter, contact and winding of stepping magnet 724, winding of relay 725 to battery. Magnet 724 operates, interrupts its own circuit and advances the brushes 727 and 728 to the next set of terminals. If the following sender is idle, the allotter switch comes to rest, but if it is busy, the switch continues until an idle sender is found. When the switch leaves the position shown, it opens the shunt around the relay 723 and this relay operates in series with magnet 731. The relay 723 opens the circuit of relay 722. Relay 722 being slow holds its armatures for an interval after the operation of relay 723 which is sufficient for certain operations to take place as will presently be described.

During the interval measured by the release of relay 722 a circuit is closed from ground through the winding of relay 735, inner right front contact of relay 723, left contact of relay 721, left front contact of relay 712, back contact of relay 709, winding of the horizontal operating magnet 710 individual to the link 708 to battery. Magnet 710 operates and effects a connection between the link 708 and the incoming circuit and also between the link and the outgoing circuit 732.

At the time the vertical operating magnet 731 operates a circuit is closed from ground through the outer contact of said magnet, conductor 740, inner left back contact of relay 805, winding of slow release relay 800 to battery. Relay 800 closes a circuit for relay 805. Relay 800 also locks in a circuit from battery through its winding and right contact, conductor 837, outer left contact of relay 838, outer left back contact of relay 832, conductor 839, outer right contact of relay 804, inner right contact of relay 805 to ground at the left front contact of relay 800.

Immediately that the connection is established through the sender selector 700 a circuit is closed from battery through the winding of the horizontal magnet 710, winding of relay 709, contacts of the switch 700, conductor 740, inner left front contact of relay 805, winding of relay 801 to ground

at the inner left contact of relay 803. The magnet 710 is held energized in this circuit under the control of the sender after the above traced energizing circuit has been opened. Relay 709, however, being shunted for the time being remains deenergized to prevent the extension of the start circuit through to the next link in the group.

After the necessary interval has expired slow relay 722 releases and opens the circuit of relays 716 and 717. Relay 717 opens the circuit of relay 723 which releases and opens the original operating circuit through the winding of relay 709. Relay 709 thereupon operates in series with the magnet 710 in the substitute holding circuit. Relay 717 opens the circuit of the vertical operating magnet 729 and also the circuit of the operating magnet 731. These two magnets release and restore the associated rods to their normal positions. The connection is held by the maintained energization of the horizontal magnet 710.

At the time the sender is first seized and relay 805 operates a circuit is closed from battery through the winding of slow-release relay 825, conductor 844, inner right back contact of relay 1004, thence over conductor 1011, conductor 843 to ground at the outer right contact of relay 805. Relay 825 operates and completes a circuit from battery through the winding of relay 824, left contact of relay 825, thence over conductor 847 to ground, through the middle right contact of relay 805. Relay 824 operates and completes a substitute holding ground on conductor 837. At the time the sender is seized another circuit is closed from battery through the winding of relay 809, conductor 861, inner right back contact of relay 903, to ground over conductor 843. Relay 809 closes a circuit from battery through the winding of relay 823, left front contact of relay 809, conductor 862, contacts of the switch 700, conductor 750, outer right front contact of relay 108 to ground. Relay 823 operates and a circuit is closed from battery through the winding of relay 819, outer front contact of relay 823 to the grounded conductor 847. Relay 819 operates and locks through its inner left contact, conductor 863 to ground through the middle right contact of relay 805. Relay 819, therefore remains energized after relays 809 and 823 become deenergized, when subsequently, the relay 903 operates on the receipt of the first digit from the operator's keyboard.

As soon as the sender is attached to the trunk a circuit is completed from ground over conductor 740, through contacts of the sender selector, thence over conductor 741, right contacts of key 119, outer left contact of relay 103, winding of relay 110 to battery and in parallel through the middle lower contact of relay 109, conductor 129, wind-

ing of relay 610 to battery. Relay 110 at its lowermost contact opens the circuit of relay 713 resulting in the release of the controlling relays in the sender selector 5 switch 700.

When the cordless operator receives the designation of the called subscriber's line, which in the present case is number 1, 3, 2, 6, she proceeds to set this number up on 10 her keyboard. Accordingly, she depresses the No. 1 key 632, the No. 3 key 633, the No. 2 key 634 and the No. 6 key 635. These keys are of the locking type and remain 15 depressed until they are released by the key release magnets 604, 605, 606 and 607. The contacts 636, 637, 638 and 639 are common to the rows 600, 601, 602, and 603, respectively and operate when any key in these 20 rows is depressed. When a key in each row has been operated, as above mentioned, a circuit is completed from ground through the contacts 636, 637, 638 and 639 through the inner right front contact of relay 610, conductor 641, inner lower contact of relay 25 109, thence through the winding of relay 116 and in parallel through the inner upper contact of relay 110 and the lower winding of relay 115 to battery. Relay 115 completes a circuit from battery through the 30 lamp 121, inner lower front contact of said relay, inner right contact of relay 116, inner lower front contact of relay 119, through the interrupter 130 to ground. The interrupter 130 causes the lamp 121 to 35 flicker. Relay 116 releases the relay 108, which in turn, releases the relay 105 to open the circuit of lamp 120. Relay 108 releases at this time since the operator has already 40 released the assignment key 118 to open the original circuit therefor.

Transfer of numerical record to the sender.

Another circuit is completed from ground 45 through the contacts 636, 637, etc., thence through the left contact of relay 609, winding of relay 629 to battery. Relay 629 operates and prepares the mechanism in Fig. 6 for transmitting codes of impulses in accordance with the depressed keys to establish 50 the record of the P. B. X. call line on the registers of the associated sender. Relay 629 completes a circuit from ground through the right back contact of relay 608, right front contact of relay 609, inner left 55 contact of relay 610, conductor 651, middle right contact of relay 629, inner right back contact of relay 627, outer right contact of relay 626, inner right contact of relay 625, left back contact of relay 627, left-hand 60 windings of relays 628 and 627 to battery. Relay 628 operates in this circuit but relay 627 being marginal does not receive sufficient current to energize. Relay 628, in operating, completes a circuit from battery, 65 through the left-hand winding of relays 627

and 628, right-hand winding of relay 627, inner right contact of relay 628 to the grounded conductor 651. The right-hand winding of relay 627, however, being shunted by the above circuit does not 70 operate. Relay 628 completes a circuit from ground through its outer right contact, conductor 642, contact of relay 621, outer right back contact of relay 613, winding of relay 612 to battery. Relay 612 operates and closes a circuit from battery through its winding and inner left contact, winding of relay 621 to ground over conductor 642. Relay 621, however, being shunted 75 does not operate at this time. 80

Relay 629 also completes a circuit from ground through the outer right contact of relay 610, conductor 643, inner right contact of relay 629, conductor 644, left back contact of relay 624, winding of relay 623 to 85 battery.

Relays 623 and 624 are constructed to operate and release slowly and in conjunction with each other they serve to measure intervals of time for the purpose of creating and transmitting impulses in accordance with the settings of the keys on the operator's keyboard to represent different digits of the wanted line. Relay 623, therefore, operates slowly in the above traced circuit and on 90 completing its operation closes a circuit from battery through the winding of relay 624, inner left contact of relay 623 to the grounded conductor 644. Relay 624 energizes in this circuit and operates slowly. When relay 624 is fully operated a circuit 95 is closed from battery through the winding and normal contact of relay 622, outer right front contact of relay 624 to the grounded conductor 644. Relay 622 operates and locks 100 through its inner left front contact to ground over conductor 644. When relay 624 completes its operation it closes a circuit from battery through a resistance and its middle right contact directly to the 110 grounded conductor 644. This circuit being in shunt of the relay 623, the latter relay commences to release slowly. When relay 623 is fully released it closes a circuit from battery through its right back contact directly to the grounded conductor 644 in 115 shunt of the relay 624. Therefore, the relay 624 commences to deenergize slowly. In this manner the relays 622 and 624 operate in 120 succession and release in succession to measure intervals of time.

While the relays 623 and 624 are releasing a circuit is completed from ground or the positive pole of battery through the outer right contact of relay 622, conductor 650, outer left contact of relay 629, conductor 672, right normal contacts of relay 630, conductor 652, middle upper contact of relay 109, conductor 131, contacts of the sender selector 700, conductor 743, normal contacts 125 130

of relay 806, conductor 842, through the windings of relays 827, 833 and 834, conductor 841, right normal contacts of relay 806, conductor 742, contacts of the sender selector 700, conductor 132, uppermost contact of relay 109, conductor 653, left normal contacts of relay 630, left back contact of relay 626, outermost right contact of relay 629, left back contact of relay 613, contacts of the key 632, through the high resistance 654 to the opposite pole of battery.

Relays 827, 833 and 834 in the sender receive the impulses from the keyboard and operate or remain inert according to the character of these impulses. Relay 834 is polarized in such a manner as to respond to positive impulses, namely, those which are transmitted when the positive pole of battery is connected to conductor 842. Relay 833 is polarized in the opposite direction and responds to impulses of a negative character. Relay 827 is marginal and operates on impulses of either polarity provided they are strong in character, but does not operate on weak impulses.

Relay 834 operates in response to the impulse while relays 623 and 624 are releasing as above described and a circuit is closed from ground through the outer right contact of relay 805, conductor 843, contact of relay 834, left back contact of relay 835, left back contact of relay 903, register relay 911 to battery. Relay 911 locks to the grounded conductor 843. After the relays 623 and 624 have fully released as above explained a circuit is closed from the grounded conductor 644, through the outer right back contact of relay 624, outer left contact of relay 622, conductor 645, left back contact of relay 625, left-hand winding of relays 626 and 625 to battery. Relay 626 operates and prepares a circuit for itself and relay 625, but the latter being shunted does not operate at this time. When relay 626 operates it opens the shunt around the right-hand winding of relay 627 and this relay operates in series with relay 628. Relay 627, in operating, completes a circuit from battery through the winding of relay 613, outer left contact of relay 612, conductor 646, outer right contact of relay 627, conductor 647 to the grounded conductor 651. Relay 613 operates and locks to the conductor 647. Relay 613 opens the shunt and permits relay 621 to operate in series with the relay 612. Another circuit is completed from battery through the resistance 648, conductor 649, winding of relay 630, outer left contact of relay 623, inner right contact of relay 624, inner right contact of relay 622 to the grounded conductor 644. Relay 630 operates and locks in a circuit from battery through the resistance 648, winding and inner left contact of relay 630 to the grounded conductor 644.

Next the relays 623 and 624 operate in succession. Relay 624, in operating, removes ground from conductor 645, whereupon relay 625 is permitted to operate in series with relay 626. While relays 623 and 624 are operating at this time a circuit is closed from the positive pole of battery over conductor 650, outer left contact of relay 629, conductor 672, left front contacts of relay 630, conductor 653, through the polarized relays in the sender as described and returning over conductor 652, through the right front contact of relay 630, conductor 656, high resistance 654, to the opposite pole of battery.

This impulse being negative and weak causes the operation of relay 833 only. Relay 833 closes a circuit from ground over conductor 843, contact of relay 833, left back contact of relay 836, left-hand windings of relays 835 and 836 to battery. Relay 835 operates but relay 836 being marginal remains deenergized. Relay 835 closes a circuit for itself including the right-hand winding of relay 836, but the latter being shunted relay 836 remains inert. Relay 835, in operating, closes a circuit from ground over conductor 843, outer right contact of relay 835, outer left back contact of relay 902, winding of relay 903 to battery. Relay 903 operates and closes a circuit from battery through its winding and the winding of relay 902, inner right front contact of relay 903 to ground over conductor 843. Relay 902 being shunted remains deenergized for the present.

After the relays 623 and 624 are operated a circuit is closed from battery through the resistance 648, middle left contact of relay 622, outer right contact of relay 624 directed to the grounded conductor 644. This circuit shunts the relay 630 which releases and interrupts the impulse being transmitted to the sender. Relay 833 thereupon releases and opens the shunt and permits the relay 836 to operate in series with relay 835.

Next the time measuring relays 623 and 624 release in succession. At the end of this period a circuit is closed from the grounded conductor 644, outer right contact of relay 624, outer left contact of relay 622, conductor 645, left front contact and left-hand winding of relay 625 to battery. This circuit shunts the relay 626 which releases. Moreover, the above traced circuit is closed for the operation of relay 630.

Next in order the relays 623 and 624 operate in succession. During this period a circuit is closed from the positive pole of battery, over conductor 672, thence through the left front contacts of relay 630, over conductor 653, through the sender and returning over conductor 652, right front contacts of relay 630, conductor 656 and resistance 654 to battery. Relay 833 operates in this circuit and at its contact closes a

- holding circuit for relay 836 in shunt of relay 835. Relay 835 releases but relay 836 at its inner right contact maintains the shunt around the winding of relay 902.
- 5 At the end of the impulse period ground is removed from conductor 645 whereupon relay 625 releases. A circuit is now closed from battery through the left-hand winding and left front contact of relay 627, inner right contact of relay 625, outer right contact of relay 628, inner right front contacts of relays 627 and 628 to the grounded conductor 651. This circuit shunts the relay 628 which releases and opens the circuit of relay 627 which also deenergizes. Moreover, the relay 630 is shunted as above explained and retracts its armatures. Relay 630 opens the circuit of relay 833, which in turn, opens the circuit of relay 836 which
- 10 removes the shunt and permits the relay 902 to operate in series with relay 903. When relay 628 releases it opens the holding circuit of relays 612 and 621. Relay 612 at its right contacts disconnects the row of keys 600 from the impulse circuit. Thus, the necessary code impulses have been transmitted from the operator's keyboard to the sender for recording the first digit of the P. B. X. called number.
- 15 Immediately that relays 625, 627, 628 and 630 have been restored as above explained, relay 628 is reenergized over the circuit already traced. Relay 628 closes a circuit from ground through its outer right contact, conductor 642, contact of relay 621, outer right front contact of relay 613, outer right back contact of relay 615, winding of relay 614 to battery. Relay 614 operates and prepares a circuit for itself in series
- 20 with relay 621, the latter relay remaining deenergized. Next the relays 623 and 624 undergo release. During this period a circuit is closed from the positive pole of battery, over conductor 672, thence through contacts of relay 630, over conductor 652, and returning over the conductor 653 through the normal contacts of relay 630, left back contact of relay 628, outer right contact of relay 629, left front contact of relay 613, left back contact of relay 615, contacts of key 633, high resistance 654 to battery. Relay 834 responds to this impulse and a circuit is closed from ground over conductor 843, contact of said relay, left
- 25 back contact of relay 835, left front contact of relay 903, outer left back contact of relay 905, winding of register relay 913 to battery. Relay 913 locks to the grounded conductor 843.
- 30 After relays 623 and 624 have fully released, relays 626, 627 and 630 are operated as heretofore described. Relay 630, in operating, interrupts the impulse being transmitted to the sender and relay 834 becomes deenergized. Relay 627, in operating, closes
- 35 a circuit from ground over conductor 647 through the outer right contact of relay 627, conductor 646, outer left front contact of relay 614, winding of relay 615 to battery. Relay 615 operates and locks to the conductor 647. Relay 615, in operating, removes the shunt and permits relay 621 to operate in series with relay 614.
- 40 Next the relays 623 and 624 undergo operation and during this period a circuit is closed from the positive pole of battery over conductor 672 and thence as traced over conductor 653 through the sender and returning over conductor 652, front contacts of relay 630, conductor 653, outer right back contact of relay 625, inner right front contact of relay 614, contacts of the key 633, low resistance 655 to battery. In this case a heavy negative impulse is transmitted and relays 827 and 833 operate. Relay 827 closes a circuit from ground over conductor 843, outer right back contact of relay 836, outer right front contact of relay 902, inner right back contact of relay 904, winding of relay 914 to battery. Relay 914 locks to grounded conductor 843. Relay 833 operates and causes the operation of relay 835 as described. Relay 835 completes a circuit from ground over conductor 843, outer right contact of said relay, outer left front contact of relay 902, outer left back contact of relay 904, winding of relay 905 to battery. Relay 905 operates and prepares a circuit for relay 904. When relays 623 and 624 have
- 45 fully operated, relay 625 energizes and relay 630 releases. Relay 630 opens the circuit of relays 827 and 833 and relay 836 operates in series with relay 835.
- 50 Relays 623 and 624 now become deenergized in succession, at the end of which time, relay 626 releases and relay 630 operates. Following this the relays 623 and 624 operate. During this period a weak negative impulse is transmitted to the sender in the manner above explained. In response to this impulse relay 833 operates and shunts the relay 835. At the end of the period relays 625, 628, 627 and 630 become released. Relay 630 opens the circuit of relay 834 which releases and permits relay 904 to operate. Relay 628, in releasing, opens the circuit of relays 621 and 614. Relay 614 disconnects the strip of keys 601 from the impulse circuit.
- 55 The apparatus is now ready to transmit impulses representing the third digit. When relay 628 again operates it completes a circuit in the manner above explained for the relay 616 which operates and prepares a circuit for relay 621 and renders the set of keys 602 effective. As soon as relays 623 and 624 have released, relays 626, 627 and 630 become energized. Relay 627, in operating, completes a circuit for relay 617 which operates and locks to the conductor

647. Relay 617 removes the shunt and allows relay 621 to operate in series with relay 616. Next the relays 623 and 624 energize and during this period a circuit is closed from the positive pole of battery over conductor 652, through the right front contact of relay 630, outer right back contact of relay 625, inner right contact of relay 616, contacts of key 634, low resistance 655 to battery.

10 relay 1002, winding of relay 1007 to battery. A heavy negative impulse is sent in this circuit operating relays 827 and 833. Relay 827 completes a circuit as above described over front contacts of relays 902 and 904, through the inner right back contact of relay 1002, winding of relay 1007 to battery. Relay 1007 operates and locks over conductors 1010, 1011 and 843 to ground. Relay 833, in operating, causes the operation of relay 835, which in turn, completes a circuit 20 in the manner explained for relay 1003. Following the impulse period of relay 625 operates and relay 630 releases. Relay 630 opens the circuit of relays 827 and 833 and relay 836 operates.

25 Following this relays 623 and 624 release, at the end of which time, relay 626 releases and relay 630 operates.

Next the relays 623 and 624 operate. During this period a light negative impulse 30 is transmitted to the sender in the manner above described. Relay 833 responds to this impulse causing the release of relay 835. After relays 623 and 624 have operated, relays 625, 628, 627 and 630 release. The impulse circuit is now open and relay 836 releases, permitting relay 1002 to operate in 35 series with relay 1003. Relay 628, in releasing, opens the circuit of relays 621 and 616.

40 Relay 628 immediately operates again and in so doing completes a circuit over contacts of relays 621, 613, 615 and 617 for relay 618. Relay 618 operates and prepares a circuit for itself and relay 621. Next the 45 relays 623 and 624 release and during this interval a circuit is closed from the positive pole of battery over the normal contacts of relay 630, conductor 652 to the sender and returning over conductors 653, 50 left normal contacts of relay 630, left contact of relay 626, outer right contact of relay 629, left front contacts of relays 613, 615 and 617, left back contact of relay 619, contacts of key 635, conductor 656, resistance 654 to battery. A positive impulse 55 is transmitted in this circuit and relay 834 responds to complete a circuit as heretofore traced over contacts of relays 903, 905, 1003 and 1005, winding of relay 1008 to battery. Relay 1008 operates and locks to the 60 grounded conductor 1011. When relays 623 and 624 release, relays 626, 627 and 630 operate. Relay 627 closes a circuit for relay 619 in an obvious manner and this latter 65 relay operates and locks to conductor 647.

Relay 619 removes the shunt and relay 621 operates in series with relay 618. Next relays 623 and 624 operate in succession. During this interval a light negative impulse is transmitted to the sender operating relay 833 which causes the operation of relay 835. Relay 835 completes a circuit in the manner above traced for relay 1005. When relays 623 and 624 have operated, relay 625 operates and relay 630 releases. Relay 833, in turn, releases causing, in turn, the operation of relay 836. Next the relays 623 and 624 become d energized, following which relay 626 releases and relay 630 operates.

Lastly, relays 623 and 624 operate and during this period, a heavy negative impulse is transmitted to the sender over a circuit which leads through contacts of the key 635 in the manner above described. In response to this impulse relays 827 and 833 operate. Relay 827 closes a circuit from the grounded conductor 843 over its contact, outer right front contact of relay 836, inner left contacts of relay 902, 904 and 1002, outer right contact of relay 1004, winding of relay 1009 to battery. Relay 1009 operates and locks to the grounded conductor 1011. Relay 833 causes the release of relay 835. At the end of the period relays 625, 628, 627 and 630 release. Relay 630 opens the impulse circuit and relay 833 and relay 827 release. Relay 833 opens the circuit of relay 836, which in turn, permits relay 1004 to operate in series with relay 1005.

Thus the complete record has been transmitted from the operator's keyboard to the registers 900, 901, 1000 and 1001. Following the transmission of the last impulse, relay 628 operates and a circuit is closed from ground over its outer right contact, conductor 642, contact of relay 621, outer right front contacts of relays 613, 615, 617 and 619, outer right back contact of relay 620, winding of relay 611 to battery. Relay 611 operates and prepares a circuit for itself and relay 621. When relay 627 operates a circuit is closed at its outer right contact and the left contact of relay 611 for operating relay 620. Relay 620 operates and locks to the grounded conductor 647. Relay 620 opens the shunt and permits relay 621 to operate in series with relay 611. When subsequently relay 628 releases it opens the circuit of relays 611 and 621. The next time relay 628 operates it closes a circuit over the contact of relay 621 and the right front contacts of relays 613, 615, 617, 619 and 620, winding of slow-to-release relay 608 to battery.

Relay 608, in operating, locks through its left contact and thence over contacts of the depressed keys in each row in parallel branches to ground. Relay 608 opens the

circuits of relays 609 and 629. Relay 629 renders the impulse sending mechanism ineffective to transmit any further impulses. Relay 608 at its right front contact closes 5 parallel circuits for the key release magnets 604, 605, 606 and 607. These magnets energize and restore the operated keys to normal. When all keys are restored, relay 608 releases. Relay 609, in releasing, 10 moves ground from conductor 651 whereby all energized relays depending upon this conductor are released.

Relay 109 which is included in circuit with relay 609 releases upon the operation 15 of relay 608 and in so doing disconnects the operator's keyboard from the trunk circuit 100. Relay 109 opens the circuit of relay 610 and this relay becomes deenergized.

20 If, at this time, the operator at the originating office has inserted her plug in the jack of the trunk 100, a circuit is completed from battery, through the right-hand winding of relay 106, right normal contacts of relay 104, lower left winding of repeating coil 101, inner right back contact of relay 103, over the ring side of the trunk 100 and returning over the tip side of said trunk through the outer right back contact of relay 103, upper left winding of relay 101, left 25 normal contacts of relay 104, left-hand winding of relay 106 to ground. Relay 106 operates and closes a circuit through the upper winding of relay 115. The lamp 121 30 continues to flicker. Relay 106 also closes a circuit from ground through its contact, through the left-hand winding of relay 117 to battery. Relay 117 operates and locks 35 through its right winding to the grounded conductor 125.

40 It will be recalled that as soon as the complete record has been received in the sender, relays 1004 and 1005 become operated. Relay 1004 at its inner right contact opens the 45 previously traced circuit of relay 825. Relay 825 is slow to release and requires an interval to retract its armature. During this interval a circuit is closed from battery through the winding of relay 832, right 50 front contact of relay 825, conductor 848, inner right front contact of relay 1004 to ground over conductor 1011. Relay 832 operates and locks through its inner left contact to the grounded conductor 843. After an 55 interval relay 825, releases and in so doing opens the holding circuit of slow relay 824. Relay 824, however, cannot release at this time since a holding circuit is provided therefor as follows: battery through the winding of said relay, conductor 864, outer right contact of relay 808, conductor 865, outermost left contact of relay 866, inner right contact of relay 819, left back contact 60 of relay 821 to ground over conductor 863.

Association of the incoming marker and 65 operation of incoming switch.

The apparatus is now in condition to associate the sender with the incoming marker shown in Fig. 12. As a matter of fact this 70 association takes place immediately that the second digit has been received and recorded on the hundreds register 901. Following the receipt of the second digit a circuit is completed from ground over conductor 843, 75 conductor 1011, inner left front contact of relay 905, conductor 915, outer right contact of relay 829, conductor 852, winding of relay 1104 to battery. Relay 1104 operates and closes a circuit from ground through its 80 right contact, outer right back contact of relay 1107, winding of relay 1108 to battery. Relay 1108 operates and locks through its right contact, outer right back contact of relay 1111, conductor 1120, contact of slow relay 1114 to ground. Another circuit is 85 closed from battery through the right-hand winding of relay 1103, left contacts of relay 1104 and relay 1106, left front contact of relay 1108, outer right back contact of relay 1111 to ground over conductor 1120. Relay 1103 operates and closes an obvious circuit 90 for relay 1107. With relay 1107 energized a circuit is closed from battery through the left winding and contact of relay 1103, left 95 back contact of relay 1105, left contact of relay 1107, winding of relay 1111 to grounded conductor 1120. Relay 1103 locks and relay 1111 operates in this circuit. Relay 1111 opens the locking circuit of relay 1108. The 100 multi-contact relay 1101 which is individual to the sender illustrated is energized to extend the conductors from the sender to the marker. The circuit for this relay may be traced from battery, through its winding, inner right contact of relay 1103, inner left contact of relay 1111, conductor 1120 to ground. Relay 1101, in operating, also closes a circuit from ground through its contact, conductor 1121, outer left contact of relay 1111, inner left back contact of relay 1113, winding of relay 1112 to battery. The connecting device 1100 is made up of a plurality of multi-contact relays each individual to a different sender. Another of these 110 relays 1102 is illustrated together with relays 1105 and 1106 relating thereto. Relay 1112, in operating, completes a circuit from ground over conductor 1120, through the inner left contact of said relay, conductor 1122, outer left back contact of relay 1246, winding of slow-to-release relay 1248 to battery. Relay 1248 operates and closes a circuit 115 for slow release relay 1247.

120 At this time a circuit is completed for the vertical operating magnet 207 which controls the row of contacts 201 of the incoming selector switch 200 in which appears the 125

incoming trunk 100. This circuit may be traced from ground through the right contact of relay 1112, conductor 1123, contacts of relay 1101, conductor 1124, inner right back contact of relay 829, conductor 853, outer right contact of relay 809, conductor 854, contacts of the switch 700, conductor 744, uppermost front contact of relay 110, conductor 160 winding of vertical magnet 207 to battery. The magnet 207 operates, rotates its associated bar and prepares the contacts in the row 201. The magnet 207 also completes a circuit from ground through its contact, conductor 214, through the windings of multicontact relays 1208, 1209 and 1210 to battery. These relays operate and connect the marker to the incoming switch 200.

It will be noted that the marker shown in Fig. 12 is provided with a number of relays, three of which 1223, 1224 and 1225 are shown. These relays are individual to groups of trunks appearing in the contacts of the different incoming switches. They are selected in accordance with the registration of the thousands register 900 in the sender in order to determine which group of outgoing trunks is needed for extending the connection through the incoming switch. While only three of these relays are shown, it is understood that there may be as many as are necessary. The relay 1225, for instance is individual to the group of trunks containing the trunk 211 appearing in the vertical row 204 of the selector 200 and in corresponding rows of other selectors. This group of trunks is identified by the thousands digit 1 which, it will be recalled, is the digit recorded on the register 900 of the sender. Therefore, since relay 911 is energized while relays 912, 916 and 917 are in released condition, register 900 prepares a circuit which may be traced from ground over conductor 1120, outer right front contact of relay 1111, outer left contact of relay 1112, conductor 1125, contacts of relay 1101, conductor 1126, inner back contact of relay 909, left back contact of relay 917, outer right back contact of relay 916, inner left back contact of relay 912, outer back contact of relay 907, conductor 918, contacts of relay 1101, conductor 1127, conductor 1226, winding of relay 1225 to battery.

With relay 1225 operated a circuit is closed from ground through the lowermost contact of said relay, conductor 1227, winding of relay 1246 to battery. Relay 1246 operates and opens the circuit of relay 1248, but this latter relay requires an interval in which to release its armatures. Relay 1246, in operating, completes a circuit from ground through its inner left contact, right front contact of relay 1247, inner upper contact of relay 1225, conductor 1228, contacts of relay 1210, conductor 1229, winding of the vertical operating magnet 208 to battery. Magnet 208 operates and prepares the contacts of the vertical row 204 representing the selected outgoing group of trunks. Magnet 208 also closes a circuit from ground through its contact, conductor 215, contact of relay 1210, conductor 1230, winding of relay 1249 to battery. With relay 1246 operated a circuit is completed from ground over conductor 1122, outer left front contact of said relay, left contact of relay 1247, conductor 1231, contacts of relay 1210, conductor 1232, middle lower contact of relay 1225, winding of multicontact relay 1207 to battery. Relay 1207 is individual to the group of trunks appearing in the row 204 and serves to associate the testing relays of the marker, with these trunks. The equipment is now in condition to make a test of the trunks outgoing from the switch 200 and also of the corresponding horizontal links. For this purpose a series of double wound test relays 1211, 1214, 1217, etc. is provided each being individual to an outgoing trunk in any group with which the marker may be associated and also associative with the corresponding horizontal links on any incoming switch 200. The relay 1211, for instance, is associative with the trunk 216 and if this trunk is busy a circuit is closed from the grounded sleeve conductor of the trunk over conductor 218, contacts of relay 1207, right contact of relay 1213, right-hand winding of relay 1211 to battery. Should the horizontal link 206 which has access to the trunk 216, be busy a circuit is closed from the grounded sleeve conductor of said link, thence over conductor 219, contacts of relay 1209, outer left back contact of relay 1213, left-hand winding of relay 1211 to battery. Relay 1211 operates when either of its windings is energized or when both are energized simultaneously. Relay 1211, in operating locks through its right winding and right contact to ground at the outer right contact of relay 1246. Relay 1211 closes a circuit for relay 1212 to the grounded conductor 1233. In this manner the test relays associative with all busy trunks or busy links are operated.

If it is assumed that the next trunk 211 in the group is idle and that the link 205 is also idle the corresponding test relay 1214 remains deenergized. After an interval slow relay 1248 releases and a circuit is completed over conductor 1122, right contact of relay 1249, right contact of relay 1248, inner right contact of relay 1246, conductor 1234, contacts of relay 1207, inner front contact of relay 1212, inner left back contact of relay 1215, winding of relay 1216 to battery. Relay 1216, operates and a circuit is completed from ground through the left contact of relay 1249, conductor 1235, contacts of relay 1207, right

front contact of relay 1212, right back contact of relay 1215, left front contacts of relay 1216, through the contacts of relay 1209, thence over conductors 1236 and 1237, winding of the horizontal operating magnet 209 to battery. Magnet 209 rotates the associated rod and completes the connection through the selector switch 200 whereby the incoming trunk 100 is connected to the link 10 205 and the link 205 is connected to the outgoing trunk 211 leading to the group selector switch 300. Immediately that the connection is effected a circuit is completed from battery through the right-hand winding 15 of magnet 209 through contacts of switch 200, over the sleeve conductor 125, conductor 124 to ground through the left contacts of key 119. The magnet 209 is held energized in this circuit after the incoming marker has released.

After an interval has elapsed following the release of relay 1248 slow relay 1247 de-energizes and opens the circuit of relay 1207. Relay 1247 also opens the circuit of 25 the vertical operating magnet 208, which in turn, releases and opens the circuit of relay 1249. With relay 1247 released a circuit is closed from ground over the inner left contact of relay 1246, right back contact of relay 1247, conductor 1239, winding of release relay 1113 to battery. Relay 1113 operates and locks temporarily through its inner left contact and the outer left contact of relay 1111 to the grounded conductor 30 1121. Relay 1113 at its outer left contact closes a circuit for relay 1114. Relay 1114 is slow to operate and slow to release and, therefore, requires an interval of time to 35 retract its armature and remove ground from conductor 1120. During this interval a circuit is closed from ground over conductor 1120, through the outer right contact of relay 1113, conductor 1128, contacts of relay 1101, conductor 1129, winding of relay 40 829 to battery. Relay 829 operates and locks through its inner left contact to ground over conductor 847, through the middle right contact of relay 805.

After the necessary interval relay 1114 45 operates and removes ground from conductor 1120 whereby the operated relays of Fig. 9 become deenergized and the sender is disconnected from the marker and the remaining energized relays in the marker and the vertical operating magnet 207 of the switch are restored to normal.

Association of the line marker and operation of the group selector and connector switches.

60 The next operation to take place is the connection of the line marker shown in Figs. 13 and 14, with the registers of the sender through the medium of the multi-contact relay connector 1301. At the time 65 relay 829 operates a circuit is closed from

ground through the left front contact of relay 800, inner right contact of relay 805, outer right contact of relay 804, conductor 839, outer left front contact of relay 832, outer left contact of relay 829, outer left 70 back contact of relay 830, conductor 855, thence in parallel through the windings of relays 906, 907, and 909 to battery.

It was hereinbefore explained that the exchange is divided into five terminal line 75 groups each serving 2,000 lines and each provided with a single line marker. It, is, therefore, necessary to determine which one of these terminal line groups is to be taken for use in completing a connection to the called line. This is done by means of the thousands register 900 upon which is recorded the thousand digit. In the present instance the digit being 1 that means that the call line appears in the first group of 80 2,000 lines. Accordingly a circuit is traceable from ground over conductor 855, as previously described, through the inner left front contact of relay 909, left back contact of relay 917, outer right back contact of relay 916, inner left back contact of relay 912, outer front contact of relay 907, conductor 919, thence through the winding of relay 1312 associated with the connecting device 1301. Relay 1312 operates and closes a circuit for relay 1316. Relay 1316 locks 85 through its right contact, outer right back contact of relay 1314, conductor 1340, contact of slow relay 1317 to ground. Relay 1316 closes a circuit from battery, through the right-hand winding of relay 1310, left contacts of relays 1312 and 1313, left contact of relay 1316, outer right back contact of relay 1314 to the grounded conductor 1340. Relay 1310 closes an obvious circuit for relay 1315. Relay 1315 closes a circuit from battery through the left-hand winding and contact of relay 1310, left back contact of relay 1311, left contact of relay 1315, winding of relay 1314 to the grounded conductor 1340. Relay 1310 locks and relay 1314 90 operates in this circuit. A circuit is now established from battery through the winding of multicontact relay 1308 which is individual to the sender shown in the drawing, outer right contact of relay 1310, inner left contact of relay 1314 to ground over conductor 1340. Relay 1308 operates and connects the sender to the line marker. Relay 1308 also closes a circuit through its 95 contact, outer left contact of relay 1314, outer left back contact of relay 1319, winding of relay 1318 to battery.

One of the first things to take place upon 100 the connection of the line marker to the sender is the closure of the circuit for the vertical operating magnet 306 of the group selector switch 300 in which terminates the selected trunk 211 outgoing from the incoming switch 200. This circuit may be 105 110 115 120 125 130

- traced from the grounded conductor 1340, inner right contact of relay 1314, contact of relay 1318, conductor 1341, contact of relay 1308, conductor 1371, lowermost contact of relay 906, conductor 870, inner right contact of relay 830, conductor 871, inner right back contact of relay 809, conductor 872, through the sender selector 700, conductor 751, conductor 161, outer left back contact of relay 112, thence over the tip conductor of the trunk 100 through the switch 200, over the tip conductor of trunk 211, contact of relay 318, winding of the vertical operating magnet 306 to battery. Magnet 306 prepares the contacts in the corresponding vertical row of the switch 300 and closes a circuit for the multicontact relay 312. Relay 312 connects the test relays of the line marker to the horizontal links of the switch 300 for testing purposes.

The record of the thousands, hundreds, tens and units digit is now transferred from the sender to the line marker. Relays 1418 and 1419 serve to determine whether the thousands digit is even or odd according to the combination in which they are operated. In the present case the digit being 1 and odd the relay 908 in the sender is operated. It will be noted that this relay is energized in parallel with the register relay 911 at the time the latter relay was operated. Accordingly, a circuit is completed from ground over conductor 1371 as previously traced, through the outermost contact of relay 908, conductor 921, contacts of relay 1308, conductor 1343, winding of relay 1418 to battery. A circuit is now closed from battery through the winding of multicontact relay 1428, right front contact of relay 1418, back contact of relay 1419, conductor 1341 to ground through the contacts of relays 1318 and 1314.

Another circuit may be traced from ground over conductor 1371, through the outermost contact of relay 913, conductor 922, contacts of relay 1308, conductor 1373, winding of relay 1414 to battery. Another circuit is closed from ground over conductor 1371, through the outermost contact of relay 914, conductor 923, contacts of relay 1308, conductor 1374, winding of relay 1415 to battery. Another circuit may be traced from ground over conductor 1371, outermost contact of relay 1007, conductor 1013, contacts of relay 1308, conductor 1375, winding of relay 1407 to battery. Other circuits may be traced from ground over conductor 1371, through the outermost contacts of relays 1008 and 1009, conductors 1014 and 1015, contacts of relay 1308, conductors 1376, and 1377, windings of relays 1410 and 1413, respectively to battery. With relays 1414 and 1415 operated a circuit is closed from ground over conductor 1341, conductor 1358, inner left contact of relay 1359, conductor 1360, inner right back contacts of relays 1417 and 1416, inner right front contact of relay 1415, inner left front contact of relay 1414, winding of relay 1426 to battery. Since both relays 1428 and 1426 are operated a circuit is closed from battery through the winding of relay 1430, contacts of relays 1428 and 1426, conductor 1433, inner left back contact of relay 1361, outer right back contact of relay 1359 to ground over conductors 1358 and 1341.

With the translator 1404 operated as above explained a circuit is completed as follows for selecting a group of ten lines appearing in the vertical row 432 of the connector switch 400 which contains the desired P. B. X. call line 438: ground over conductors 1341 and 1358, through the outer right back contact of relay 1359, inner left back contact of relay 1361, conductor 1433, contact of relay 1430, inner back contacts of relays 1409 and 1408, inner right front contact of relay 1407, inner left back contact of relay 1406, conductor 1439, contacts of relay 1428, contacts of relay 1426, conductor 1440, winding of the vertical operating magnet 415 to battery. The magnet 415 operates its associated rod and prepares the contacts of all lines of the vertical row 432. The magnet 415 in addition completes a circuit from ground through its contact, conductor 440, thence in parallel through its windings of multicontact relays 1420 and 316 to battery. Relay 1420 is individual to the connector switch 400 and serves to connect the units register 1401 to the multicontact relay device 410. The relay 316 is individual to the particular group of trunks outgoing from the group selector switch 300 which leads to the connector switch 400 and which serves to connect the testing relays of the marker with the sleeve conductors of these trunks. Immediately that the relay 316 operates it closes a circuit for the vertical operating magnet 308 which controls the contacts of the group of trunks outgoing from the switch 300 to the connector 400.

Magnet 308, in operating, closes a circuit from ground through its contact and a contact of relay 312, conductor 323, winding of slow release relay 1321 to battery. Relay 1321 operating closes a circuit from ground over conductor 1341, conductor 1358, outer right back contact of relay 1359, outer contact of relay 1321, conductor 1362, left back contact of relay 1337, outer left contact of relay 1361, winding of slow-to-release relay 1338 to battery. Relay 1338 closes a circuit from ground over conductor 1358, through its inner left contact, conductor 1363, winding of slow release relay 1323 to battery. Relay 1323 operates and closes a circuit from battery, through the winding of slow relay 1324, right front contact of relay 1323 to the grounded conductor 1341. Relay 1324 closes

a circuit for relay 13256 which operates and locks to ground on conductor 1364.

With the apparatus in its present stage of operation a test is made of a group of trunks 5 extending between the group of selector 300 and the connector 400 to ascertain a particular one thereof that is idle coincidental with the idle condition of the associated idle link in the switch 300. If the first trunk 320 in 10 the selected group is busy a circuit is closed from the battery through the right-hand winding of the test relay 1334, inner right contact of the relay 1336, conductor 1365, contact of relay 316 to the grounded test conductor of the busy trunk 320. If the link 303 associated with the trunk 320 is also busy, a circuit is closed from battery through the left winding of relay 1334, outer left back contact of relay 1336, conductor 1366 15 contacts of relay 312 to the grounded test conductor of the busy link 303. Either winding of the relay 1334 when energized is sufficient to operate the same and this is true of the succeeding test relays in the group. 20 Relay 1334, in operating, locks through its right winding, conductor 1349, outer right back contact of relay 1359 to ground over conductor 1358. Relay 1334 closes a circuit for relay 1335 extending to the grounded 25 conductor 1349. If the next trunk 321 in the group and its associated link is busy or if both are busy, the corresponding test relay 1331 is operated in a similar manner and causes the operation of relay 1332. Assuming however, that the next trunk 322 is idle 30 and that the corresponding link 305 is also idle the related test relay 1328 remains deenergized.

A circuit may now be traced from the 40 grounded conductor 1341, conductor 1358, outer right back contact of relay 1359, inner contact of relay 1321, conductor 1367, inner left front contacts of relays 1335 and 1332, inner left back contact of relay 1329, winding 45 of relay 1330 to battery. With relay 1330 operated a circuit is closed for the vertical operating magnet 414 in the connector switch 400. This circuit may be traced from ground over conductors 1341 and 1358, 50 thence through the outer right back contact of relay 1359, outer contact of relay 1321, conductor 1362, outer right contact of relay 1330, middle right contact of relay 1329, contact of relay 316, conductor 324, winding of the operating magnet 414 to battery. Magnet 414 prepares the contacts in its associated row 430 and also closes a circuit from ground through its contact, conductor 418, contacts 55 of relay 316, winding of relay 1337 to battery. Relay 1337, in operating, opens the circuit of relay 1338, which commences to release.

While the foregoing operations are taking 60 place a test is made to determine that the call is for a P. B. X. group of trunks. At

the time relay 1420 operates it closes a circuit from battery through the winding of relay 1435, contact of relay 1420, conductor 1360, inner left contact of relay 1359 to the grounded conductor 1358. Relay 1435 operates and completes a circuit from ground over conductor 1360, contact of relay 1435, outer right contact of relay 1410, outer right contact of relay 1413, outer right back contacts of relays 1412 and 1411, conductor 1436, contacts of relay 1420, winding of multi-contact relay 411 to battery. Relay 411 operates and a circuit is closed as follows for horizontal test magnet 420 controlling the test link 403 which is common to the group of horizontal trunks having access to the P. B. X. call line 438: battery through the winding of magnet 420, contacts of relay 411, conductor 460, left front contact of relay 1337, conductor 1362, and thence to ground over the path previously traced. Magnet 420 effects connection between the horizontal test link 403 and the contacts in the vertical rows 430 and 432. This results in the closure of a circuit from battery through the winding of relay 443, connecting block 444, contacts in the row 432, conductor 455, contacts in the row 430, conductor 447, to the grounded conductor 1341. The relay 443 is individual to the called group of trunks and operates when the connector switch 400 is taken to seize the call line 438. Relay 443 locks through its inner left contact to the conductor 1341. During the time the connector is being operated and relay 443 is energized, slow relay 1338, is maintaining its armatures attracted. Hence when the relay 443 operates a circuit is closed from the grounded conductor 1341, through the outer left contact of relay 443, conductor 448, right contact of relay 1338, winding of relay 1359 to battery. Relay 1359 operates and locks through its inner right contact to the conductor 1358.

It will be noted that relay 1369 was operated in a circuit from battery through its winding, inner right back contact of relay 1359, conductor 1358, conductor 1341, through contact of the relay 1118 to ground as that previously described at the time relay 1359 was first energized. When as above described relay 1359 operates it opens the circuit of relay 1369 which being slow to release requires a definite interval to retract its armatures. Relay 1359, in operating, removes ground from conductors 1360, 1342, and 1349. The removal of ground from these conductors results in the release of relay 1430, the vertical operating magnet 415, relay 1426, relay 1435, relay 411 and magnet 414 and all energized testing relays in the marker. Magnet 415 removes ground from conductor 440 causing the release of relays 1420 and 316. Relay 411 opens the circuit of the horizontal test

magnet 420. With magnet 414 deenergized the operating circuit of relay 1337 is opened. Relay 316 in releasing, opens the circuit of the vertical operating magnet 308. Thus, 5 the seizure of the P. B. X. call line and the operation of relay 1359 causes the release of the connector switch and the release of the group of trunks outgoing from the group selectors 300 to such connector switch 10 and also the disassociation of the line marker from the connector switch. However, the vertical operating magnet 306 remains operated and the testing relays in the marker remain associated with the 15 group selector switch through the multi-contact relay 312.

After an interval following the operation of relay 1359 relay 1369 becomes deenergized and a circuit is closed from battery 20 through the winding of relay 1361, right contact of relay 1361, inner right front contact of relay 1359 to the grounded conductor 1358. Relay 1361 operates and closes a circuit for the vertical operating magnet 25 on the particular connector switch in which appears the first idle P. B. X. trunk in the group, in the present case it will be assumed that the first two trunks in order, trunks 436 and 437 in the group are busy, while 30 the third trunk 439 is the first idle one. Since the trunks 436 and 437 are both busy, the corresponding individual relays 450 and 451 are energized to mark the trunks as 35 busy. Relay 452 individual to the idle trunk 439, however, is deenergized to mark the trunk as idle. Accordingly, the circuit closed by relay 1361 may be traced from ground over conductors 1341, over conductors 1341 and 1448, outer right contact of 40 relay 1361, conductor 1470, middle right contact of relay 443, left back contact of relay 461, left front contacts of relays 450 and 451, left back contact of relay 452, winding of the magnet 416 to battery. 45 Magnet 416 operates and prepares the contacts in the row 433 and closes a circuit by way of conductor 440 as previously traced for relays 316 and 1420. Relay 316 again closes a circuit for vertical magnet 50 308, which in turn, recloses the circuit of relay 1321.

Another test is made of the trunks leading between the selector 300 and the connector 400. Provided the trunk 322 is the first idle one the previously traced circuit is completed for the vertical operating magnet 414. Magnet 414 causes the re-operation of relay 1337.

60 Relay 1361 closes another circuit from ground over conductor 1443, through the inner right front contact of said relay, conductor 1471, winding of multicontact relay 1446 to battery. Relay 1446 relates to groups of P. B. X. trunks and serves in conjunction 65 with relay 1420 to operate the device 410

in accordance with the units location of the selected idle trunk in the switch 400. With both relays 1420 and 1426 operated a circuit may be traced from ground over conductor 1358, through the outer right front 70 contact of relay 1359, left contact of relay 1369, conductor 1370, innermost front contact of relay 443, right back contact of relay 461, right front contact of relays 450 and 451, right back contact of relay 452, conductor 453, contact of relay 1446, contact of relay 1420, winding of relay 413 to battery. Relay 413 associates the test relays 1422, 1424, etc. with the respective horizontal links 407, 408, etc. in the group having 75 access to the idle P. B. X. trunk 439. If the first link 407 is busy a circuit is closed from battery through the right winding of relay 1422, left contact of relay 1421, contact of relay 413 to the grounded sleeve conductor of link 407. Relay 1422 operates and locks through its left winding and contact to the grounded conductor 1342. If the next link 408 is idle the corresponding 80 test relay 1424 remains deenergized. At the time relay 1359 first operates a circuit is closed from battery through the winding of relay 1323, conductor 1363, outer left contact of relay 1359, inner right back contact of relay 1361 to the grounded conductor 1443. Relay 1323 operates and in the manner above 85 described causes the operation of relay 1324. Relay 1325 is still energized since it is locked at the grounded conductor 1364. When relay 1361 subsequently operates it opens the 90 circuit of relay 1323 which commences to release. After an interval has elapsed relay 1323 deenergizes and opens the circuit of relay 1324. Relay 1323 also closes a circuit from the grounded conductor 1341, through 95 the right back contact of relay 1323, right contact of relay 1322, outer left contact of relay 1325, conductor 1372, inner right front contacts of relays 1335 and 1332, inner right back contact of relay 1329, left front contacts of relay 1330, contacts of relay 312, through the winding of the horizontal magnet 311 to battery. Magnet 311 operates 100 and establishes a connection between the incoming trunk 211 and the outgoing trunk 105 322, through the link 305. Immediately that the magnet 311 operates a circuit is closed from battery through the winding of relay 317, through the contacts of the switch 300 and thence to ground over the circuit 110 above traced. Relay 317 operates and immediately locks through the left contact over the grounded sleeve conductor of trunk 211. Moreover, magnet 311 locks through its 115 right hand winding, contacts of the switch 300, through the left contact of relay 317 to the grounded sleeve conductor of the trunk. Relay 317 closes a circuit for relay 318 which opens the circuit of the vertical 120 operating magnet 306. 125 130

Still another circuit is traceable from the grounded conductor 1341, through the right back contacts of relays 1323 and 1322, inner left contact of relay 1325, conductor 1351, right front contact of relay 1422, right back contact of relay 1424, winding of relay 1423 to battery. Relay 1423 operates and the grounded conductor 1351 is extended through the right contact of relay 1422, 10 thence through contacts of relay 413, through the left-hand winding of the horizontal operating magnet 423 to battery. The magnet 423 locks in a circuit through its right winding, contacts of the switch 15 400, thence over the grounded sleeve conductor of the trunk 322.

After an interval following the release of relay 1323 slow relay 1324 becomes deenergized and closes a circuit from ground over 20 conductor 1364, back contact of relay 1324, right contact of relay 1325, winding of the marker release relay 1319 to battery. Relay 1319 operates and closes a circuit for relay 1317. Relay 1317, however, being 25 slow requires an interval before it retracts its armature. During this time a circuit is established from ground through the contact of relay 1317, right contact of relay 1319, conductor 1353, through the contacts 30 of relay 1308, conductor 1354, winding of relay 830. Relay 830 operates and locks through its inner left contact to the grounded conductor 847. Relay 1319, in operating, opens the circuit of relay 1318 35 which removes ground from the conductor 1341, bringing about the release of the several relays in the line marker which have been held in circuits depending upon this grounded conductor. After an interval relay 1317 operates and removes ground from 40 conductor 1340 causing the release of the remaining operated relays and magnets. Relay 1308 is also released to disconnect the register sender from the line marker. With 45 the vertical magnets 306, 308, 414 and 416 all released as a result of the disconnection of the line marker the connection is held through to the selected P. B. X. trunk by the maintained operation of the horizontal 50 magnets 311 and 423. Thus the connection has been extended to the P. B. X. trunk 439 and the individual relay 452 operates over the sleeve conductor to identify this 55 trunk as busy in case a subsequent connection is attempted in the same group.

Release of the sender.

When relay 830 operates a circuit is closed 60 from battery through the winding of relay 821, outer left contact of relay 830, outer left contact of relay 829, outer left front contact 832, conductor 839, to ground as above traced. Relay 821 operates and locks 65 temporarily through its inner right contact to the grounded conductor 839. Relay 821

at its left back contact opens the holding circuit of slow relay 824. Relay 824 releases and removes ground from conductor 837. Relay 821 also closes a circuit from battery 70 through the winding of relay 803, left front contact of relay 821, conductor 863 to ground. With relay 803 operated and the ground removed from conductor 837 slow relay 800 becomes deenergized. Relay 800 75 opens the circuit of relay 805, which in turn, removes ground from the several holding conductors to permit the release of all energized relays in the sender and register circuits. The removal of ground from the conductor 740 causes the release of the horizontal 80 operating magnet 710 in the sender selector switch 700 whereby the sender is disconnected from the trunk 100.

Prior to the time the sender selector switch 700 releases to disconnect the sender, a circuit is closed from ground through the outer right front contact of relay 830, conductor 858, left back contact of relay 809, conductor 862, contacts of the switch 700, conductor 750, outer right back contact of relay 108, winding of relay 112 to battery. Relay 112 operates and locks to the grounded sleeve conductor 125. Relay 112 at its left contacts completes the tip and ring conductors of the trunk through to the right-hand windings of the repeating coil 101.

When the sender is discharged in the manner above explained ground potential is removed from conductor 741, and consequently, relay 110 releases. Relay 110 disconnects the lamp 121 from the interrupter 130 and connects said lamp directly to ground at its inner lower back contact. The lamp 121 discontinues its flickering and burns steadily.

Ringing current is now applied to the called trunk. To accomplish this the operator in the distant office by any well known means transmits ringing current over the incoming trunk 100. This results in the operation of the ringing relay 102. Relay 102 closes a circuit from battery through the winding of relay 111, contact of relay 102, to ground at the back contact of relay 107. Relay 111 operates and locks through its inner lower contact, thence over parallel branches, one of which extends through the winding of relay 113 and the other through the contacts of relays 113 and 114 to the grounded conductor 125. Relay 113 being shunted does not operate at this time. The circuit for applying ringing current may be traced from the ringing source 137, winding of relay 114, lowermost front contact of relay 111, inner left contact of relay 112, 115 thence over the ring of the line and returning through the outer left front contact of relay 112 to ground at the uppermost front contact of relay 111. When the operator at the private branch exchange answers relay 114 operates and opens the shunt 120 130

around the winding of relay 113. Relay 113 operates and a circuit is closed from battery through the contact and winding of said relay to the grounded conductor 125. Relay 113 locks and shunts out relay 111 which releases and disconnects ringing current from the line. When relay 111 releases relay 107 is included in series with the line and may operate to close a circuit for relay 104. Relay 104 disconnects the relay 106 from the tip and ring conductors of the incoming trunk 100, relay 106 remaining energized.

When conversation is completed the called subscriber in hanging up his receiver opens the circuit of relay 107 which releases relay 104 and relay 106 is again connected across the tip and ring conductors of the trunk 100. When the operator at the distant end takes down the connection, relay 106 releases and opens the circuit of the upper winding of relay 115. Relay 115 releases since the circuit through its lower winding is opened, a circuit is now closed from battery through the lamp 120, inner upper back contact of relay 115, middle right contact of relay 116, left front contact of relay 117, interrupter 135 to ground. Another circuit is closed from battery, through the lamp 121, inner lower back contact of relay 115, outermost right contact of relay 116, through the interrupter 135 to ground. Due to the interrupter 135 the lamps 120 and 121 flash to advise the operator that the connection is no longer required. The operator thereupon manipulates the disconnect key 119 to open its contacts. The operation of key 119 removes ground potential from the conductors 124 and 125 whereupon all energized relays together with the horizontal operating magnets 209, 311 and 423 are de-energized and the operated switches are released to break down the connection.

45 *Establishment of a connection to busy trunks of a private branch exchange group.*

It will be assumed next that the call incoming over the trunk 100 is one from a long distance or toll point and of such importance that it should be extended over a trunk in the P. B. X. group regardless of whether all trunks may be busy at the time. The operator, realizing the importance of the call, prepares the equipment for the no-test operation. To do this she first sets up the number on the numerical keys, as above explained, and then depresses the no-test key 640.

60 It will be recalled that immediately following the transmission of the code impulses representing the last digit of the number from the operator's keyboard to the sender, relays 625, 626, 627 and 628 become released. Relay 628 in operating again completes a circuit for relay 611. During the next time

measured interval, while relays 623 and 624 are releasing, a circuit is closed as follows due to the fact that the no-test key 640 is operated: ground over conductor 650, thence over conductor 672 through the right normal contacts of relay 630, conductor 652, through the sender and returning over conductor 653, left normal contacts of relay 630, left contact of relay 626, outer right contact of relay 629, left front contacts of relays 613, 615, 617 and 619, left contact of relay 620, contacts of key 640, conductor 656, high resistance 654 to the opposite pole of battery. Due to this additional impulse the relay 834 in the sender operates and a circuit is closed from ground over conductor 843, contacts of said relay, left back contacts of relay 835, left front contacts of relays 903, 905, 1003 and 1005, conductor 1016, winding of relay 822 to battery. Relay 822 operates and locks through its left contact to the grounded conductor 863. Following this the operator's keyboard equipment is released in the manner fully described hereinbefore.

When the register sender is subsequently associated with the line marker, a circuit is closed as follows due to the fact that the relay 822 in the sender is operated: ground, through the right contact of said relay, conductor 873, contacts of relay 1308, winding of relay 1378 to battery. Relay 1378 operates and locks to the grounded conductor 1341. Later, when the relay 443 is operated, as previously related, a circuit is established from ground, through the inner lower contact of relay 1378, conductor 1379, outermost right contact of relay 443, winding of relay 461 to battery. Relay 461 erases the effect of the usual test made to determine the busy or idle condition of the first P. B. X. trunk 436 in the group. In other words, the relay 461 determines that this first trunk shall be selected notwithstanding that it may be busy and its test relay 450 is operated.

When the relay 1361 operates as described, a circuit is closed from ground over conductor 1443, thence through the outer right contact of relay 1361, conductor 1470, middle right contact of relay 443, left front contact of relay 461 to the winding of the operating magnet 416. With relay 1369 released, another circuit is closed from ground over conductor 1358, outer right front contact of relay 1359, left contact of relay 1369, conductor 1370, inner right contact of relay 443, right front contact of relay 461, conductor 462, contacts of relay 1446, and 1420 to the winding of relay 411 to battery. Relay 411 associates the test relays with the group of horizontal links 401, 402, etc. having access to the first P. B. X. trunk 436.

From this point on the apparatus functions in the manner clearly described hereinbefore and the switch 400 is operated to

seize the trunk 436 whether it is busy or not, and the connection is extended to the desired private branch exchange.

5 *Distribution of P. B. X. trunks among the connector switches.*

If desirable, the trunks of a private branch exchange group may be distributed to appear in more than one connector switch.

- 10 The particular P. B. X. group shown is arranged to appear both in the connector switch 400 and the connector switch 500. The first three trunks 436, 437 and 439 appear in the switch 400, whereas the last 15 trunks 523 and 524 appear in the vertical row 521 of the connector switch 500. From an inspection of the circuits it will be found that in case all three of the trunks which appear in the switch 400 are busy, a test 20 will be made of the trunks 523 and 524, and if one of these are idle, the same will be seized and the connection reestablished under the control of the marker through the connector switch 500.

25 What is claimed is:

1. In a telephone system, a group of equivalent lines arranged to be marked and selected, means for identifying the lines when busy, automatic switches for extending connections over the lines of said group in accordance with their marked condition, and means for governing the operation of said switches to extend a connection over 30 one of said lines regardless of its busy condition.

2. In a telephone system, a group of equivalent lines arranged to be marked and selected, means for identifying the lines when busy, automatic switches for extending connections over the lines of said group after they have been marked, a sender mechanism for controlling said switches, and means for altering the control of said sender over the switches to extend a connection 40 over one of said lines whether such line is busy or idle.

3. In a telephone system, a group of private branch exchange trunks, means for marking said trunks for determining the 50 first idle one in order to be taken for use, automatic switches, means normally effective for controlling said switches to select the particular trunk found to be idle, and

means for altering the control over said switches to seize one of said trunks when 55 the same is busy.

4. In a telephone system, a group of equivalent lines, means for marking said lines to determine an idle one to be taken for use, an operator's position, automatic 60 switches, means normally effective for controlling said switches to select an idle one of said lines, and means controlled by the operator for altering the control over said switches to select one of said lines whether 65 the same is busy or idle.

5. In a telephone system, a group of trunks, automatic switches, an operator's position, means controlled by the operator for operating said switches to select and 70 extend a connection over the first idle trunk in the group, and means under the control of the operator for altering the control over said switches to select a trunk in said group whether the same is busy or idle. 75

6. In a telephone system, a plurality of groups of equivalent lines arranged to be marked for selection, automatic switches, means for setting said switches to select a group of said lines, means for releasing the 80 connection, means for reoperating said switches to select an idle line in the selected group, and means for rendering said switches effective to select a busy line in the selected group. 85

7. In a telephone system, a group of trunks, a relay for each trunk for indicating the first idle trunk in the group, automatic switches for extending a connection over an idle trunk, and means for altering 90 the control of said automatic switches to disregard the indication of said relays and to seize one of said trunks whether busy or idle.

8. In a telephone system, a group of 95 trunks, means for marking said trunks to determine an idle one, coordinate switches for extending a connection over an idle trunk, and means for changing the operation of said switches in order to extend a 100 connection over one of said trunks whether the same is busy or idle.

In witness whereof, I hereunto subscribe my name this 8th day of August A. D., 1923.

EARL S. GIBSON.
